SEPARABLE END STOP FOR SLIDE FASTENERS

Filed April 5, 1938

UNITED STATES PATENT OFFICE

2,216,794

SEPARABLE END STOP FOR SLIDE
FASTENERS

Frederick Ulrich, Bayonne, N. J., assignor to
Conmar Products Corporation, Bayonne, N. J.,
a corporation of New Jersey

Application April 5, 1938, Serial No. 200,067

7 Claims. (Cl. 24—205)

This invention relates to slide fasteners, and more particularly to a separable end stop for use at the lower end of slide fasteners which are to be fully separated, as for example, when used 5 on coat sweaters, wind-breakers, or the like.

The primary object of my invention is to generally improve fully separable slide fasteners, and more particularly the separable bottom end stop therefor. In most popular form, these end 10 stops comprise a body member secured to one of the tapes and having a socket dimensioned to receive a pin formed on the other tape, said pin being insertible through the slider while the slider is in lowermost position resting against the body of the end stop. These bodies have 15 been made of sheet metal and have also been die-cast, but difficulty arises in either case. A more particular object of the present invention is to overcome prior difficulties, which I do by 20 providing a body for the separable end stop which is made of solid stock rolled to form appropriate channels therein and to give the same the desired cross-section. This rolled stock may be appropriately treated and severed in a die to form a 25 piece which is bent upwardly in U-shape, said U-shaped piece being clamped to one of the tapes. The resulting product is stronger and cheaper to manufacture than either a die-cast body or a sheet metal body, and possesses further 30 advantages over the sheet metal body, first, in presenting a more attractive appearance; and second, in avoiding the necessity for using special rivets, bent tongues, or the like, for holding the legs of the U against spreading. In fact, one 35 feature and object of the present invention is to dispense with any such additional fastening means, and in accordance with the present invention, the rolled stock is made heavy enough and hard enough and is so shaped in cross- 40 section, that the bend or bottom of the U is stiff enough to effectively prevent opening or separation of the legs of the U.

While the inherent strength of the body is adequate to hold the same clamped tightly on the 45 fastener, I prefer to guard against the possibility of longitudinal movement of the body relative to the tape, for otherwise the body may under abuse or rough handling, be slid forcibly down off the end of the fastener. With this object in view, the body is provided with a tang for engaging the tape. More specifically, I form 50 a tang on one side of the body and an aperture on the other side of the body opposite the tang. No attempt is made to bring the tang itself into 55 the aperture, but instead it merely displaces

some of the fabric of the tape sidewardly into the aperture, and the fabric material itself acts as the locating projection or dowel which effectively prevents longitudinal movement of the body relative to the tape. 5

Still another object is to provide means above the slider body adapted to be received within the slider for helping locate the slider relative to the body during insertion of the pin. This may consist of a short stud or sleeve secured to the 10 bead of the tape immediately above the body, but I find that it is still better to make the stud or sleeve relatively long, say, equal in length to the pin, in which case much of the length of the stud is clamped within the body. The side 15 walls of the stud are in such case cut away or notched at the aforesaid tang and aperture of the body, in order not to interfere with the functioning thereof, and in order to help permanently secure the tape, the stud and the body 20 together. 25

To the accomplishment of the foregoing and such other objects as will hereinafter appear, my invention consists in the slide fastener and separable end stop elements and their relation 25 one to the other, as hereinafter are more particularly described in the specification and sought to be defined in the claims. The specification is accompanied by drawing, in which:

Fig. 1 is a side elevation of a slide fastener 30 equipped with a separable end stop embodying features of my invention;

Fig. 2 is a similar view taken in section through the body of the end stop with the pin removed from the body; 35

Fig. 3 is a horizontal section taken in the plane of the line 3—3 of Fig. 1;

Figs. 4 and 5 are explanatory of the method of 40 rolling the material or stock for the body;

Fig. 6 is a plan view of a piece of stock being 40 fabricated to form the body;

Fig. 7 is a transverse section taken in the plane of the line 8—8 of Fig. 6 prior to bending the tang;

Fig. 8 is a section taken in the plane of the 45 line 8—8 of Fig. 6 after bending the tang;

Fig. 9 is a section taken in the plane of the line 9—9 of Fig. 6;

Fig. 10 is a side elevation showing the manner in which the body is bent up to finished U-shape; 50

Fig. 11 is a perspective view showing the construction of the stud; and

Fig. 12 is a perspective view explanatory of the construction at the bottom end of the pin.

Referring to the drawing, and particularly to 55

Fig. 1, the slide fastener comprises stringers 12 and 14, a slider 16, and a separable bottom end stop generally designated 18. Stringers 12 and 14 each include a fabric tape 20 having a beaded edge 22, consisting of cords stitched on opposite sides of the tape at the edge thereof. A series of interlockable elements 24 are secured along the beaded edges 22 of the tapes. The slider 16 is slideable over the elements 24, and functions in the usual manner to open or close the fastener. When the slider 16 is moved to lowermost position, it bears against and rests on the upper edge of the body 26 of end stop 18, as is indicated by the broken line position of the slider shown in Fig. 2. At this time the elements 24 have all been disengaged from one another, and to complete the full opening or separation of the stringers 12 and 14, it is merely necessary to remove the lower end of stringer 14 from body 26 and the slider 16, as is clearly shown in Fig. 2.

To facilitate the insertion of the lower end of stringer 14 through slider 16 and into body 26, it is provided with a pin 28. This consists of a strip of sheet metal bent around bead 22 and clamped in place. The lower end of tape 20 is preferably bent upwardly, as is indicated at 30 before applying the sleeve-like pin 28, thus strengthening and stiffening the material at the lower end of the stringer and guarding against unraveling of the threads at the bottom of folded edge 32. In order to avoid undue bulk within pin 28, the cords which are sewed at the edge of the tape to form the bead 22 are removed from the upwardly bent end 30 so that the material clamped within pin 28 includes two tape edges and only two cords, as is clearly shown at the right-hand part of Fig. 3, rather than four cords, as would be the case if the cords were not removed from the upwardly folded end 30. The outside dimension of the pin 28 is kept small enough to pass freely through the channel of the slider 16. The lower end of the pin is preferably closed by metal tongues which protectively shield the tape, and the construction at this point will be clearly evident from inspection of Fig. 12, in which it will be seen that the side walls of pin 28 are provided with short inwardly turned tongues 34, while the inside wall is provided with a relatively long, outwardly turned tongue 36. Tongues 34 are preferably kept short so that tongue 36 will be disposed therebetween, and all three tongues together form a substantially enclosed metallic end for the pin 28.

The body 26 is preferably made of a piece of solid material formed with collateral channels. A section through the material is clearly shown in Fig. 9, and it will be observed that there are two channels 38 and 40, channel 38 being larger than channel 40. The material is bent upwardly on a center or fold line indicated at 42 in Fig. 6. In Fig. 10 the piece of stock is shown preliminarily bent upwardly to V-shape, as is indicated in broken lines. The legs may at this time be at an angle of, say, 58°. The bending step at this time is performed away from the fastener, and the piece of stock is then applied to stringer 12 and its legs or walls 44 and 46 are clamped together against the lower end of the stringer, thus locking the same in place. No special rivet or bent tongue is needed to hold the legs of the U in desired closed condition, for the section through the material is adequate in area and in its channel-shaped distribution of metal, to hold

the legs stiffly in desired position, with no danger of spreading or separation.

The stock is preferably a continuous piece of metal which is rolled to the desired double channel shape. This is schematically indicated in Figs. 4 and 5, in which it will be seen that the piece of metal 50 is passed between rolls 52 and 54, thus working and hardening the metal in addition to squeezing the same into the desired channeled configuration.

The resulting continuous strip of rolled stock is severed into suitable lengths, as is indicated by the line of severance 56 in Fig. 6, and is then folded as was previously described in connection with Fig. 10.

The body 26 of the end stop may be clamped directly on the beaded edge of stringer 12, and I have made successful end stops with that construction. In such case the channel 40 is made considerably smaller relative to the channel 38 than is indicated in the present drawing.

The pin 28 is longer than the body 26 and projects thereabove even when inserted to the limit of its movement, as is indicated in Fig. 1. The lowermost elements 24 are disposed an appreciable distance above body 26 in order to make certain of opening or separation of the elements when the slider 16 is moved to its lowermost position. The projection of pin 28 above body 26 helps strengthen the tapes and stiffen the same against undue flexibility between the pin and the lowermost element. For generally similar reasons, it is desirable to provide a stud 60 projecting upwardly somewhat above body 26. The slider moves over the stud 60 when in lowermost position, and the stud is therefore made small enough to enter the channel of the slider.

The stud may be short, but it is preferable to make it in the form of a long sleeve generally resembling the pin 28, said sleeve being received within and permanently secured to the body 26. A piece of sheet metal is folded about the beaded edge of stringer 12 and is securely clamped in place. The lower end may be finished by an inturned tongue 62, as is clearly shown in Fig. 11. The lower end of the tape 64 is preferably folded upwardly before applying the stud 60 to the tape, for reasons heretofore described in connection with the fold 30 on the other tape. In this case, as in the case of the fold 30, the cords forming the bead of the tape are preferably freed and cut away from the upwardly turned fold 64 in order not to add too great a bulk of material inside the stud. Only one tongue is provided at the lower end of stud 60 because it is not necessary to finish this end as well as the lower end of the pin 28, for the stud remains permanently locked within the body 26 and is not repeatedly inserted and removed, as is the case with pin 28. The stud is preferably made equal in length to the pin 28 so that the projection of the stud above the body is approximately equal to the projection of the pin above the body. The stud is preferably given a flat-sided or squared cross-section because this helps keep the slider 16 in approximately the same plane as the body 26 while inserting the pin 28 through the slider and body 26. The channel 40 rolled into the stock from which the body is formed is appropriately enlarged to receive the stud 60, but this channel is still substantially smaller than the channel 28, as will be clear from Fig. 9, so that the body 26 may be clamped hard against stud 60 in order to securely lock the tape, the stud and the body together, while at the same

time providing ample clearance in channel 38 for free insertion or removal of pin 28. It will be observed in the drawing that the center or partition flange 66 is triangular or wedge-shaped, and in Fig. 3, it will be seen how these flanges 66 exert a wedging action on stud 60 when the body 26 is clamped against the stud.

While the sides of the body grip the stud and tape with sufficient strength to prevent spreading of the body and possible loss of the same, I find that it is nevertheless desirable to anchor the body against the possibility of movement in a direction longitudinal of the tape. This is so because under forcible or abusive use of the fastener, the body 26 might be slid off the stud 60 even without appreciable opening up or spreading of the walls 44 and 46 of the body.

To accomplish the desired results, I provide a tang 70 formed integrally with and projecting inwardly from the wall 44 of the body. An aperture 72 may be cut through the other wall 46 of the body at a point opposite tang 70. The tang 70 is intentionally made short and no attempt is made to force the same through the fabric or into the aperture 72. Instead, the tang 70 displaces the tape material sidewardly and jams the same into the aperture 72, as will be clearly understood from inspection of Fig. 3 of the drawing. In this way the fabric forced into aperture 72 acts as a locating member or detent and effectively prevents longitudinal movement of body 26 relative to the tape.

The construction as so far described would be applicable whether or not stud 60 is employed. When the stud is employed, as in the present case, it is preferably notched or cut away, as is indicated at 74 in Figs. 2 and 11. The stud is cut away in this manner on both sides, and tang 70 passes through the notch on one side, while the displaced tape material passes through the notch on the other side, as is shown in Fig. 3.

The method of making the tang 70 and aperture 72 will be clear from examination of Figs. 6 through 9 of the drawing. In making the tang 70, the flange 76 is preliminarily cut away at 78, leaving a reduced amount of material, as will be clear from inspection of Fig. 7. The remaining material is then incised and bent to form the tang 70, as will be clear from inspection of Fig. 8. The aperture 72 is cut through the stock by a simple punching operation. It will be understood that the operations here described for forming the tang 70 and aperture 72 may be and preferably are performed in a suitable die which operates on the stock while it is still a continuous wire or ribbon, the final operation being to sever the finished piece at the cut-off line 56. With some additional elaboration, the die may also function to bend the cut-off piece to the V form shown in broken lines in Fig. 10, and this dispenses with one extra handling of the stock. The V-shaped pieces are applied directly to the fastener, the latter having been preliminarily equipped with stud 60.

It is believed that the arrangement, operation, and method of manufacture of my improved separable bottom end stop, as well as the many advantages thereof, will be apparent from the foregoing detailed description. It will also be apparent that while I have shown and described my invention in a preferred form, changes and modifications may be made in the structure disclosed, without departing from the spirit of the invention defined in the following claims.

I claim:

1. A separable bottom end stop for a fully separable slide fastener comprising tapes having interlockable elements secured along the edges thereof, a slider, and a separable bottom end stop including a sheet metal member folded about the edge of one of said tapes at the lower end thereof and acting as a pin, and a body comprising a piece of metal with parallel collateral channels folded upwardly to U-shape, one of said channels being smaller than the other, said larger channel being dimensioned to freely receive the aforesaid pin, and said smaller channel being clamped on the other tape, the cross-section of said channel-shaped material being such that the body is stiff enough at the bend to hold the sides of the body in the desired U-shape without necessitating the use of additional fastening means to keep the sides of the U from spreading apart, and means to anchor the body on the tape, said means including a short, blunt tang formed integrally with and bent inwardly from one side of said body, and an aperture cut through the opposite side of said body at said tang, whereby said tang forces the material of said tape into said aperture.

2. A separable bottom end stop for a fully separable slide fastener comprising tapes having interlockable elements secured along the edges thereof, a slider, and a separable bottom end stop, said stop including a sheet metal member folded about the edge of one of said tapes at the lower end thereof and acting as a pin, a sheet metal member folded about the edge of the other of said tapes at the lower end thereof and acting as a stud, and a body comprising a piece of metal with parallel collateral channels folded upwardly to U-shape, one of said channels being smaller than the other, said larger channel being dimensioned to freely receive the aforesaid pin, and said smaller channel being clamped on the aforesaid stud, the upper end of said stud projecting upwardly above the body to receive the slider, and means to anchor the body on the tape, said means including a short, blunt tang formed integrally with and bent inwardly from one side of said body, an aperture cut through the other side of said body opposite said tang, and said stud being cut away on both sides at said tang and aperture, whereby said tang forces the material of the tape into said aperture.

3. A separable bottom end stop for a fully separable slide fastener comprising tapes having interlocking elements secured along the edges thereof, a slider, and a separable bottom end stop, said stop including a pin at the lower end of one tape, and a piece of rolled metal of variable-thickness channeled cross section folded to U-shape and clamped on the edge of the other tape, the inner face of said metal piece having a pair of continuous collateral channels extending along the entire inner surface of the U, one of said channels receiving the pin, and the other being clamped on the other tape.

4. A separable bottom end stop for a fully separable slide fastener comprising tapes having interlocking elements secured along the edges thereof, a slider, and a separable bottom end stop, said stop including a pin at the lower end of one tape, and a piece of rolled metal of variable-thickness channeled cross section folded to U-shape and clamped on the edge of the other tape, the inner surface of said metal piece having a pair of continuous collateral channels

- channels extending along the entire inner surface of the U, one of said channels being smaller than the other, said larger channel being dimensioned to freely receive the aforesaid pin, and said smaller channel being clamped on the edge of the other tape, the outer surface of said metal piece having a configuration from the channeled inner surface.
5. A separable bottom end stop for a fully separable slide fastener comprising tapes having interlocking elements secured along the edges thereof, a slider, and a separable bottom end stop, said stop including a sheet metal member folded about the edge of one of said tapes at the lower end thereof and acting as a pin, a substantially similar sheet metal member folded about the edge of the other of said tapes at the lower end thereof and acting as a stud, and a piece of rolled metal of variable-thickness channeled cross section folded to U-shape and clamped on the aforesaid stud, the inner face of said metal piece having a pair of continuous collateral channels extending along the entire inner surface of the U, one of said channels being smaller than the other, said larger channel being dimensioned to freely receive the aforesaid pin, and said smaller channel being clamped on the aforesaid stud, the outer surface of said metal piece having a configuration different from the channeled inner surface.

6. A separable bottom end stop for a fully separable slide fastener comprising tapes having interlocking elements secured along the edges thereof, a slider, and a separable bottom end stop, said stop including a pin at the lower end 5 of one tape, and a piece of rolled metal of variable-thickness channeled cross section folded to U-shape and clamped on the edge of the other tape, the inner face of said metal piece having a pair of continuous collateral channels 10 extending along the entire inner surface of the U, one of said channels receiving the pin, and the other being clamped on the other tape, and means to anchor the metal piece on the tape, said means including a tang formed integrally 15 with and bent inwardly from one side of the metal piece.

7. An end stop housing of a separable bottom stop for a fully separable slide fastener, said housing comprising a rolled metal member 20 folded to U-shape, said U comprising substantially parallel legs and a connecting base portion, the inner face of the legs and base portion having a pair of collateral channels, the channels continuously extending along the inner surface 25 of the legs and across the connecting base portion of the U, the outer surface of said housing having a configuration different from the channeled inner surface.

FREDERICK ULRICH. 30
